UNITED STATES PATENT OFFICE.

GEORGE A. WEBER, OF NEW YORK, N. Y., ASSIGNOR TO THE WEBER RAIL-WAY JOINT MANUFACTURING COMPANY, OF NEW YORK, N. Y., A CORPORATION OF WEST VIRGINIA:

RAIL-FASTENING.

SPECIFICATION forming part of Letters Patent No. 735,630, dated August 4, 1903.

Application filed February 28, 1903. Serial No. 145,539. (No model.)

To all whom it may concern:

Be it known that I, GEORGE A. WEBER, a citizen of the United States, and a resident of the borough of Manhattan, city, county, 5 and State of New York, have invented certain new and useful Improvements in Rail-Fastenings, of which the following is a specification, accompanied by drawings.

My invention relates to rail-fastenings; and 10 its objects are to improve upon the construction of such apparatus and render the fastening more efficient and strong, while affording provision for the adjustment of the rail.

Further objects of my invention will hereinafter appear; and to these ends my invention 15 consists of a rail-fastening for carrying out the above objects, embodying the features of construction, combinations of elements, and arrangement of parts, substantially as hereinafter fully described and claimed in this specification and shown in the accompanying drawings, in which—

Figure 1 is a transverse sectional view of a rail-fastening embodying my invention. Fig. 25 2 is an end view of the same with the rail in transverse section. Figs. 3 and 4 are plan and side views of one of the rail-clips.

Referring to the drawings, a shoe angle or plate C is shown in connection with the rail-30 fastening. In this instance the base of the rail rests upon the shoe-angle C, and a portion of the base extends within the reversely-bent portion R of the shoe-angle. One of the rail-clips, as D, bears upon the shoe-angle C and upon one side of the base of the rail and is secured in position by means of the bolt E, provided with the nut L. At the 35 other side of the fastening interlocking connections are provided between the shoe-angle C and the rail-clip T. As shown in this instance, one edge of the shoe-angle is provided with the hook U, while the clip T is fashioned to coöperate with said hook by having formed therein another hook V. 40 The rail-clip T is also provided with an extended portion W, which bears upon the top of the reversely-bent portion R of the shoe-angle C. The bolt E, provided with the nut L, secures the clip T in position, and the 45 heads of the bolts E bear upon the bearing 50

plate X beneath the tie. The bolts E extend substantially vertically through the tie B; but I am not to be understood as limiting myself to vertical bolts, for they may extend at an angle through the tie, if desired. The 55 bolt-apertures in the clips D and T are elongated, as shown, to afford provision for adjusting the clips relatively to the bolts to permit adjustment of the shoe-angle C and also to permit adjustment of the rail relatively to the shoe-angle.

Obviously some features of my invention 60 may be used without others and my invention may be embodied in widely-varying forms.

Therefore, without limiting myself to the construction shown and described nor enumerating equivalents, I claim, and desire to secure by Letters Patent, the following:

1. In a rail-fastening, the combination of a 70 shoe-angle, a rail supported thereon, one edge of said shoe-angle being provided with a hook, rail-clips for clamping the rail, one of said clips having a hook coöperating with the hook on the edge of the shoe-angle, and bolts 75 for securing the clips, for substantially the purposes set forth.

2. In a rail-fastening, the combination with the tie, of a shoe-angle comprising a plate one end of which is reversely turned to form a 80 clamp, a rail supported upon said shoe-angle, one of the flanges of the rail being thrust beneath the reversely-turned portion of the shoe-angle, said shoe-angle being provided with a hook adjacent to the reversely-turned portion 85 thereof, a rail-clip for clamping one flange of the rail to the shoe-angle and tie, and another rail-clip provided with a hook coöperating with the hook on the shoe-angle for clamping the shoe-angle to the tie, and bolts ex- 90 tending through the tie and clips for securing them in position, for substantially the purposes set forth.

In testimony whereof I have signed this specification in the presence of two subscribing witnesses.

GEORGE A. WEBER.
